(57) **CLAIM**

The ornamental design for a frame for glasses, as shown and described.

DESCRIPTION

FIG. 1 is a front view of the frame for glasses in a rest position; and,

FIG. 2 is a front view of the frame for glasses in a working position.

The broken lines shown in the drawings depict portions of the frame for glasses and form no part of the claimed design. The additional broken lines shown in a circle format are for the purposes of disclosing the boundaries of the claim and form no part of the claimed design.

1 Claim, 1 Drawing Sheet
